UNITED STATES PATENT OFFICE.

WILHELM WAGNER, OF AIX-LA-CHAPELLE, GERMANY.

INHALER.

SPECIFICATION forming part of Letters Patent No. 629,482, dated July 25, 1899.

Application filed January 18, 1899. Serial No. 702,550. (No model.)

To all whom it may concern:

Be it known that I, WILHELM WAGNER, M. D., a citizen of Germany, residing at 58 Boxgraben, Aix-la-Chapelle, Kingdom of 5 Prussia, Germany, have invented certain new and useful Improvements in Ether-Masks; and I do hereby declare the following to be a full, clear, and exact description of the invention, such as will enable others skilled in the 10 art to which it appertains to make and use the same.

This invention relates to an ether-mask in which a funnel-shaped cover projecting inward is provided with a valve opening inward for admitting ether and air for breathing, introduced into said funnel-shaped cover, and with very fine sieves, made of non-absorbent material, stretched across the interior of the receptacle, between said valve and 20 an outlet-valve arranged laterally on the surface of the mask, for taking up and distributing the ether.

The accompanying drawing shows a mask according to this invention in vertical section. 25 This mask consists of a metal casing A, closed at the top by a funnel-shaped cover B, the other side, which is applied to the face of the person to whom the anesthetic is to be administered, being suitably shaped and edged 30 with rubber tube to render it air-tight when applied to the face. The funnel-shaped cover B is provided at its lowest point with an opening a, closed by a spring-controlled non-return valve b in such manner as to allow air 35 to enter the interior of the mask, but to prevent it from escaping. At the side of the casing is arranged an opening c, closed by a non-return-valve outlet d, arranged outside and working in the opposite direction—i. e., 40 enabling air to escape, but preventing it from entering. Between the two valves there are stretched in the interior of the casing in a transverse direction one or more very fine metallic sieves D. When the mask is being 45 used, the anesthetic falls onto and becomes distributed over said sieves. It not only moistens the fine wires of the sieves, but also

fills up the meshes, so that one or more transverse layers of ether are thus produced in the casing.

When the mask is placed on the face of the person to be anesthetized, atmospheric air passes, when the patient is breathing, through the inlet-valve b into the mask, but cannot enter the respiratory organs without passing through the ether-layers aforesaid, and thus considerably accelerates the vaporizing of the ether. This vaporizing is all the quicker, since the ether is placed not, as in ordinary masks, on absorbing material—such 55 as gauze, flannel, sponge, wool, &c.—but on a non-porous material. According to the laws of physics all substances having a great absorbing property give up the substances absorbed with difficulty, whereas the vaporization of ether on the sieves according to this invention is incomparably quicker.

Experiments with the new masks have shown that a completely insensible state has been reached by means of ether in one and 70 one-half to four minutes, whereas in other masks it requires a much longer time. Not only the ether alone quickly becomes vaporized, but its vaporization is accelerated by the admission of an unlimited quantity of atmospheric air, so that the patient does not simply breathe vapors of ether, but air saturated with ether.

The anesthetic is, as already stated, supplied by introducing it into the funnel-shaped 80 cover B, whence it enters the interior of the valve b and remains there as long as the valve is closed. The valve opens only as long as breathing proceeds in a regular manner. As soon, however, as the breathing ceases the 85 valve remains closed, and ether cannot penetrate into the interior of the mask. By means of this arrangement the valve constitutes a device for automatically regulating the anesthetic-supply, which is of the highest importance, as its admission when breathing has ceased is not only undesirable, but dangerous to the life of the patient.

Having now fully described my invention,

what I claim; and desire to secure by Letters Patent, is—

An ether-inhaler consisting of a casing provided with a funnel-shaped inwardly-sloping cover, an inwardly-opening valve arranged at the lowest point of the cover, an outwardly-opening valve arranged in the side of the casing and fine sieves of non-absorbing material extending across the casing between

the valves, substantially as shown and described.

In testimony whereof I affix my signature in presence of two witnesses.

WILHELM WAGNER.
